UNITED STATES PATENT OFFICE

2,566,108

CHAIN WRENCH

Joe C. Anderson, Houston, Tex.

Application June 7, 1947, Serial No. 753,184

2 Claims. (Cl. 81—68)

1

This invention relates to new and useful improvements in a chain wrench.

An object of the invention is to provide a chain wrench for use on pipe, and the like, having novel features permitting the wrench to be readily and easily applied and adjusted to the pipe to be turned.

Another object of the invention is to provide a chain wrench for use on pipe and the like having a novel means for holding the jaws of the wrench in engagement with the pipe to rotate the pipe in one direction and means for quickly and easily reversing said holding means so that the pipe may be rotated in the opposite direction without necessitating the detachment and reattachment of the chain of the wrench from its encircling position around the pipe to be turned.

The above and other objects will be apparent from the following description and illustrated in the accompanying drawings, wherein:

Figure 1 is a side elevational view of the wrench.

Figure 2 is a plan view of the reversing mechanism, and

Figure 3 is a side elevational view of the wrench, partly in section.

Referring now more particularly to the drawings, the numeral 1 designates the wrench handle, which has an outwardly projecting lug 2 through which the adjusting bolt 3 is mounted. An adjusting nut 4 is mounted on the lower end of said bolt 3 and the chain 5 has one end thereof pivotally mounted on the other end of said bolt 3. A pair of jaws, 6, 7, are mounted on said handle 1 by means of suitable stud bolts, as 9, 10, the upper ends of said jaws being inwardly and downwardly tapered toward the center thereof, each side having the oppositely faced teeth 11, 12. A notch 13 between said sides provides a pipe rest adapted to engage the pipe when the wrench is in neutral position.

A cradle comprising a pair of outwardly and upwardly extended arms 14, 15, mounted on the axle 16 is mounted between the jaws 6, 7, the respective ends of the axle 16 extending through the ports 17, 18 in the jaws 6, 7. The portion of said axle 16 between said arms 15, 14, is enlarged and has a flat bottom. The upper wall of the ports 17, 18 has a notch 19 midway between the ends thereof to receive said axle 16 when the cradle is in neutral position.

A chamber 20 is provided in the upper end of the handle 1 in which the coil spring 21 is mounted. Seated on the upper end of said coil spring 21 is a plunger 22, the upper end of said plunger, 22, being beveled. The spring 21 urges

5 said plunger 22 against the flat bottom of said cradle and, when the cradle is moved to a position on either side of neutral, out of said notch 19, the cradle is tipped, moving one end of the arms 14, 15, upwardly.

The chain 5 is placed around a pipe, as 23, and the jaws 6, 7 moved tightly against said pipe, and the chain then secured to the jaws as by moving the reduced portion of a link between 10 two inwardly projecting studs as 24, 24 on the lower ends of the jaws 6, 7, and then the slack, if any, is taken out of the chain by means of the adjusting nut 4. The cradle is then manually moved, by means of the projecting ends of 15 the axle 16, to either side of the neutral position in the slots 17, 18, depending on the direction of rotation of the pipe desired. When moved to the position shown in Figure 3, the plunger 22 will be urged by the spring 21 against the cradle 20 rocking the arms 14, 15 on said axle 16 and forcing the pipe 23 over against the teeth 11 and the wrench then may be manipulated to turn the pipe in the desired direction, the teeth 11 gripping the pipe on the forward stroke and sliding 25 easily over the surface of said pipe on the back stroke. If it is desired to change the direction of rotation, the cradle is manually moved to the position opposite the neutral position by the operator placing his fingers against the projecting ends of the axle 16 and overcoming the pressure of the spring 21 and sliding the cradle in 30 the slots 17, 18, to the opposite side of the neutral position, where plunger 22 will apply pressure to the cradle, moving the arms against the pipe thus urging the pipe against the oppositely faced teeth 12, reversing the rotating 35 direction when the wrench is again manipulated.

The embodiments of the invention herein described and shown are to be regarded as illustrative only and it is to be understood that the invention is susceptible to variation, modification and change within the scope of the appended claims.

What I claim is:

45 1. In a chain wrench, a handle, a pair of jaws mounted on opposite sides of said handle, at one end thereof, an adjustable chain mounted on said handle and adapted to embrace the pipe to be rotated, a pipe receiving cradle having a 50 transverse axle, the extended ends of said axle being reduced, said jaws having elongated ports through the sidewalls thereof in which the ends of said axle are mounted, said ends of said axle extending beyond said ports to provide means 55 for sliding said axle and cradle transversely of

said jaws, a chamber in said handle, a coil spring in said chamber, a plunger mounted on said coil spring and in yieldable contact with said cradle so that when the cradle is moved to either side of the plunger axis, the plunger will bias the cradle tending to rock it about the axle, moving the pipe into contact with one of the jaws.

2. In a wrench, a handle, one end of said handle being rounded, a pair of toothed jaws mounted one on each side of said handle at said rounded end, means for guiding a pipe to be rotated into contact with one side of said jaws, said guiding means having upwardly extending arms and having a transverse axle mounted in and extending through transverse elongated ports in said jaws, a chamber in said rounded end of said handle, a spring loaded plunger mounted in said chamber in contact with said guiding means, said plunger constantly exerting pressure on said guiding means to selectively rock said cradle when it is moved to a transverse extremity of

said ports, thus moving the pipe to be rotated into contact with said jaws.

JOE C. ANDERSON.
